CLAIM

I claim the ornamental design for a product dispenser, as shown and described.

DESCRIPTION

FIG. 1 is a top, front, left side perspective view of a product dispenser showing my new design;

FIG. 2 is a top, front, left side perspective view thereof shown in the open position with the tear strip portion removed;

FIG. 3 is a left side elevational view of the product design in FIG. 1;

FIG. 4 is a right side elevational view thereof;

FIG. 5 is a top plan view thereof;

FIG. 6 is a bottom plan view thereof;

FIG. 7 is a front elevational view thereof;

FIG. 8 is a rear elevational view thereof;

FIG. 9 is a left side elevational view of the product dispenser in FIG. 2;

FIG. 10 is a front elevational view thereof; and,

FIG. 11 is a top plan view thereof.
